UNITED STATES PATENT OFFICE

2,529,725

BOTTLE CARTON

Grover C. Currie, Charlotte, N. C., assignor to
 Dacam Corporation, Charlotte, N. C., a corporation of North Carolina

Application September 10, 1948, Serial No. 48,624

3 Claims. (Cl. 229—52)

1

This invention relates to a carton for carrying bottled beverages and the like and more especially relates to an improved blank and method of cutting a blank so as to result in the least loss of paper stock and also whereby the blank may be folded to form a very rigid carton or container having hand holes in its end walls so that either one of the end walls can be seized by inserting some of the fingers of a hand through an opening to thereby carry the carton filled with bottled beverages at an angle with relation to the vertical, but not at sufficient angle to cause the bottles to have any tendency to fall from the carton.

It is an object of this invention to provide a bottle carton, the blanks of which are cut from a sheet of paper stock and with a minimum of loss as what is cut from one carton forms a portion of another carton blank thus resulting in practically no loss of paper stock.

Some of the objects of the invention having been stated, other objects will appear as the description proceeds, when taken in connection with the accompanying drawings, in which:

Figure 1 is a plan view of a piece of paper stock showing how the carton blanks are cut from the paper stock;

Figure 2 is an elevation of one of the blanks cut from the paper stock and before the same is folded;

Figure 3 is an isometric view showing the blank partially folded into carton form;

Figure 4 is an isometric view showing the blank erected but with the flaps in the handle openings turned inwardly towards each other for better illustrative purposes;

Figure 5 is an end view of the carton shown in Figure 4 and showing it in partially collapsed condition.

Figure 6 is a top plan view of the carton showing its shape when filled with bottles, which are represented by dotted lines.

Referring more specifically to the drawings, the numeral 10 indicates a blank piece of paper stock of suitable rigidity from which the carton blanks are cut, this paper stock usually having what is called a liner appearing on the outside portion of a finished carton, being a laminated piece of paper stock, though it is quite evident the carton may be cut from stock not having a liner on one side thereof.

The paper stock 10 is fed through a cutting and scoring machine which cuts the blanks one after another, or, if the die is sufficiently large, several of the blanks at one operation. In Figure 1 the

2

point of cutting the blanks broadly indicated at 11, is indicated along the dotted lines 12 to produce the blank 11 and at the same time the stock is cut along the partially oval-shaped lines 14 to form the handle opening. The cut blank at the same time that it is cut from the stock is scored.

Also, suitable accurate cuts are made in the top of the end walls of the carton along the lines 15 and 16. Of course, the ends of the carton are cut along the lines 17 and 18. At the same time the blank stock is cut along the line 12, 14, 15, 16, 17 and 18, the blank is properly scored along the lines 20 and 21 to define bottom flaps 23, and these flaps, if desired, can be scored along the lines 24 and 25 if the carton is to have its bottom sealed before the bottles are placed therein.

However, in the event the carton is to be used in a crating machine such as shown in the patent application of Grover C. Currie et al., for Method and Means of Placing Articles in Cartons, Serial Number 788,602, filed November 28, 1947, the score lines 24 and 25 would not be impressed on the carton blank, because the assembled carton would have downwardly depending

unclosed flaps as shown in Figure 3, but in the event that it is to be used for placing of bottles in the carton by hand, then the bottom flaps would be secured to each other and would occupy the position shown in Figures 4 and 5 and thus the score lines 24 and 25 would coincide with each other so the bottom flaps which are secured to each other could be folded upwardly inside the carton along line 27 as shown in Figure 5 and Figure 4.

At the same time the carton is cut from the stock and the score lines 20, 21, 24 and 25 are formed, other score lines are also formed in the blank. Score lines 30 and 31 are formed in the end wall 32 to define the end wall with relation

40 to side wall 33 and side wall 34 and score lines 35 and 36 are also formed to define end wall 37 from side wall 34 and a gluing flap 38. Also score lines 40 and 41 are formed in end wall 32 and score lines 43 and 44 are formed in end wall 37 so that,

45 since the overall length of the side walls 33 and 34 is less than the space occupied by three bottles, it permits the bottles to bulge the central portion of the carton end walls 32 and 37 outwardly and thus produces a rounded corner effect for the carton.

50 A score line 46 is centrally disposed in end wall 32 and a centrally disposed score line 47 is formed in end wall 37 so that the end walls may fold along the lines and project outwardly when the carton is in collapsed condition ready for

shipping so that the space between score line 46 and score line 31 and score line 46 and score line 30 will collapse against each other, pivoting along the score lines 46 while the portion of the end wall between end wall 37 and score lines 47 and 36 and also that portion between 47 and score line 35 will pivot along score line 47 and rest face to face against each other when the carton is collapsed and with the bottom flaps of course extending downwardly and being collapsed face to face against each other.

As previously described, the cut lines indicated at 14 in Figure 1 produce finger opening flaps 50 and 51 and the blank is scored along lines 52 and 53 to allow pivoting of the flaps 50 and 51 inwardly or outwardly to the position shown in Figure 4, or the reverse of the position shown, for carrying the carton when it is filled with bottles.

The end wall 32 is also scored transversely along score lines 55 and 56 and the end wall 37 is scored along lines 57 and 58 so that that portion of the end walls above lines 55 and 57 may be folded downwardly and inwardly against the inner side of the end walls 32 and 37 and glued against the inner surface of end walls 32 and 37 and the flap 60 and flap 61 appearing above score lines 56 and 58 will pivot along the lines 56 and 58 along with the finger opening flaps 50 and 51 to which the flaps 60 and 61 are glued.

In erecting the carton, the flap 38 is disposed on the inside of the outer portion of the side wall 33 and glued thereto which is the only gluing operation necessary to erect the carton after the top of the end walls have been folded along the lines 55 and 57 to cause the portions of the end walls appearing thereabove to be glued to the inner surface of the end walls and at the same time the flaps 60 and 61 will be glued to the inner surfaces of finger opening flaps 50 and 51 respectively. In some instances these flaps will not be glued but will be turned over and maintain this position by the curvature of the handle only. The blank shown in Figure 2 has its inner surface visible, that is what will become the inner wall surface of the carton and in order for a single gluing operation to carry out the application of all necessary adhesive, a glue spot 65 is placed on the outer portion of side wall 33 and glue spots 66 and 67 are placed on the upper end wall portions appearing above the score lines 55 and 57 so that when the flap 38 is brought to the inside adhesive surface 65 of the side wall 33, the carton will be assembled and the end walls will be folded downwardly on the inside surface of the end walls along the lines 55 and 57 to adhesively secure the downturned portion of the end walls to the inner surface of the end walls and to secure the tabs 60 and 61 to the upper portions of the finger opening tabs 50 and 51 as is illustrated in Figure 4.

The purpose of the score lines 40, 41, 43 and 44 is to produce a rounded or beveled effect at the four corners of the carton when filled with bottles, and since the length of the side walls 33 and 34 is less than the space occupied by three bottles placed side by side, it is evident in Figure 6 that when the bottles are placed in the carton, the corners will be rounded or beveled as shown in Figure 6.

In the drawings and specification there has been set forth a preferred embodiment of the invention, and although specific terms are employed, they are used in a generic and descriptive sense only, and not for purposes of limitation, the

scope of the invention being defined in the claims.

I claim:

1. A paper carton comprising a pair of side walls and a pair of end walls with one of the end walls having a flap extending therefrom adapted to be secured to one end of one of the side walls and each of the side walls having downwardly depending bottom flaps hingedly secured thereto and each of the end walls having a finger opening therein for the reception of the fingers of a hand for carrying the carton filled with bottles, each of the side walls having cut away portions at their upper edges conforming in contour to the contour of the lower edges of the bottom flaps and each of the end walls having a convex upper surface and a concave lower surface of the same curvature, the top portions of the end walls being scored transversely for folding down onto the inside surface of the end walls, the upper portions of the end walls having glue spots therein for securing the folded down upper portion of the end walls, the extreme upper portion of the end walls being scored transversely and having cut portions extending from the ends of the last named score line to the upper edges of the end walls, whereby the extreme upper end of each end wall can be folded into the finger openings in the end walls, each end wall being scored vertically medially thereof and being scored at the junction point with the side walls and each end wall also being scored vertically a short distance away from each hinge line scoring at the ends of the side walls to thus provide beveled corner portions to the carton when filled with bottles having a collective overall dimension greater than the length of the side walls, the medial vertical score lines of the end walls allowing outward bulging of the end walls to thus allow the carton to be folded flat with the two side walls having their inner surfaces disposed against each other and the inner surfaces of the end walls being disposed against each other in folded position.
2. In a structure according to claim 1, the bottom flaps being provided with longitudinally horizontally extending score lines which are adapted to coincide with each other when the bottom flaps are secured together, to thus allow the bottom flaps to be folded upwardly into the carton and to lie in face to face relation when the carton is in collapsed condition.
3. A bottle carton comprising a pair of end walls and a side wall disposed between the pair of end walls and a second side wall extending from one side of one of the end walls remote from the side to which the other side wall is joined, one of the end walls at its side remote from its junction point with the first intermediate side wall having a glue flap extending therefrom and adapted to be glued to the free end of the second side wall, each of the end walls having a convex upper surface and a concave lower surface, the concavity of the lower edge of an end wall being identical to the convexity of the upper end of the end wall, the upper edges of each side wall being concave, a depending bottom flap hingedly attached to the lower edges of each side wall, the contour of lower edges of the bottom flaps being identical to the contour of the upper edges of the side walls, the side walls being hingedly connected to the end walls, and the upper portions of the end walls having a cut away flap forming a finger opening and the upper ends of each of the end walls being scored transversely by a pair of score lines the lowermost of which serve as a folding point to fold the upper portion of the

end walls downwardly against the inner surface of the end walls and the uppermost transverse score line in the upper portion of each end wall serving to allow the uppermost portion of each end wall to be bent inwardly into the finger opening when the upper portions of the end walls are bent downwardly against the proximate surfaces of the end wall.
